W. H. KESSEL

COAT COLLAR AND METHOD OF FORMING THE SAME

Filed Dec. 30, 1925

Inventor
W. H. Kessel,

By Clarence O'Brien,

Attorney

UNITED STATES PATENT OFFICE.

WILLIAM H. KESSEL, OF LOUISVILLE, KENTUCKY.

COAT COLLAR AND METHOD OF FORMING THE SAME.

Application filed December 30, 1925. Serial No. 78,358.

This invention relates to a coat collar construction, and has more particular reference to a new, novel, and simple method of forming the same, the primary object of the invention residing in such a method whereby the collars may be formed almost entirely by machines, and yet have the appearance of an entirely hand made product, thus reducing the cost of manufacture in the hand appearing made coats that are universally preferred to the machine made coats, but are nevertheless not exclusively used on account of the prohibitive prices in so far as the majority is concerned.

It is well known that the machine made type of coat collar is very thick and bulky at its free edges, thus preventing the collar from lying flat with respect to the shoulder and neck portions of the coat which considerably detract from the appearance of the garment and really demonstrates the fact that the same is of the machine made type.

In following my method, collars may be constructed almost entirely through use of a machine but regardless of this fact, said free edges of a collar formed by the present method will be relatively thin, in fact as much if not more so than the hand made type of collar and this in a relatively inexpensive manner when compared with the cost of producing collars entirely by hand.

Obviously, an additional object of the invention is the provision of such a method of coat collar construction that will permit the manufacture of a relatively great number of collars within an equal amount of time required in the construction of but a few collars when the same are constructed entirely by hand.

In the drawings wherein like reference characters indicate corresponding parts throughout the different views:

Figure 1 is a rear side elevation of a collar partially constructed in accordance with the present method.

Figure 2 is a fragmentary front side elevation of the collar, a portion of the coat material being broken away,

Fig. 3 is a view similar to Fig. 2, but disclosing the collar forming material strip in reverse position prior to the turning of the same, after the coat material and the lining have been stitched by machine at three of its edges.

Fig. 4 is a greatly enlarged vertical section taken substantially upon the line 4—4

of the finished portion of the collar shown in Fig. 1, and

Fig. 5 is a similar section taken upon the line 5—5 of Fig. 3.

In clearly describing my invention, reference will first be made to the structural details of a collar formed by my method, said collar being shown in Figs. 1 to 5 inclusive. Said collar includes a strip of material 5 of the same goods from which the coat body is formed, the same being of any conventional collar design. The collar further comprises a strip of suitable stiffening material 6, preferably canvas of the identical shape of the collar material strip 5 that is in a manner hereinafter described secured to said collar material throughout its upper and end edges as is the case in practically all coat collars of today.

The formed collar further constitutes the provision of a strip of lining material 7 also secured to the three edges of the main collar material in such a manner and with such respect to the main collar material and the lining, as to present a collar having the appearance of an entirely hand made product.

In carrying out my method the strip of lining 7 is laid on its inner face upon the strip of stiffening material 6 and then machine basted thereto as indicated by the reference character 8 in Fig. 5. The lining strip 7 is of slightly lesser dimensions than the stiffening strip 6 in order that the upper and end edges of the same will be in slight inward spaced relation with the similar edges of the stiffening strip 6, Fig. 3.

The basting between the lining and stiffening strip is so regulated that the edges of the strip will be unconnected, Figs. 2 and 5.

The stiffening strip is then laid upon the strip of material 5, the lining strip 7 being in between as clearly shown also in Figs. 3 and also Fig. 5, after which the stiffening strip and material strip 5 and 6 respectively are joined at their upper end edges by machine stitching 9.

The collar thus formed is then turned inside out, it being noted from a consideration of Fig. 4, that the fold line of the outer coat material strip 5 is in slight spaced relation with the row of stitching 9, this fold line being indicated by the reference character 10 in Fig. 4, while the fold line in the stiffening material 6 is directly adjacent the point of stitching as indicated by the reference char-

acter 11 in the same figure. This manner of reversing the partially formed collar as shown in Fig. 5, will permit the lining strip 7 to be brought into engagement with the fold line of the collar material strip 5, Figs. 1 and 4, after which the lining strip and the material strip may be bound together by hand stitching 11', Fig. 1.

It will thus be seen that the free edge of a collar constructed in accordance with the present invention will be of but slightly greater thickness than the body of the collar for thus presenting an edge similar to the entire hand constructed collar which is greatly preferred for reasons above set out.

Having thus described my invention, what I claim as new and desire to secure by Letters Patent is:—

A method of forming coat collars that includes the provision of a strip of main collar forming material, a stiffening strip, and a lining strip, the lining strip being of lesser

dimension than the stiffening strip, said method consisting of first basting the lining strip to the stiffening strip throughout an area within the upper and end edge portions of the strip so that the upper and end edge portions are unconnected, then laying the stiffening strip upon the main collar forming material strip with the lining strip interposed therebetween, and stitching the upper edge and end portions of the collar forming material strip and the stiffening strip together, then turning the strips inside out so that the stiffening strip will be disposed between the other two strips, the fold of the collar forming strip being disposed outwardly of the fold of the stiffening strip, and finally stitching the upper and end portions of the lining strip to the main collar material forming strip at the fold of said last mentioned strip.

In testimony whereof I affix my signature.

WILLIAM H. KESSEL.
